UNITED STATES PATENT OFFICE.

GEORGE ZISTER, OF CHICAGO, ILLINOIS.

NON-REFILLABLE BOTTLE.

SPECIFICATION forming part of Letters Patent No. 760,836, dated May 24, 1904.

Application filed January 11, 1904. Serial No. 188,581. (No model.)

To all whom it may concern:

Be it known that I, GEORGE ZISTER, a citizen of the United States, residing at Chicago, in the county of Cook and State of Illinois, have invented new and useful Improvements 5 in Non-Refillable Bottles, of which the following is a specification.

This invention relates to non-refillable bottles and like vessels, and has for its object to 10 provide a simple device to be placed in the neck of a bottle which will not prevent the liquid contents from being freely discharged therefrom, but will prevent the bottle from being fraudulently refilled.

15 In the drawings, Figure 1 is a sectional elevation of the upper part of a bottle embodying the improved features. Fig. 2 is a plan of a perforated diaphragm to be inserted in the neck part of a bottle, and Fig. 3 is a view 20 in perspective of a perforated diaphragm and valve.

A represents the body of a bottle, and B the neck part thereof, which is provided interiorly with an annular groove 4 for the retention 25 therein of a stationary diaphragm 5, provided throughout its surface with numerous perforations 6. This diaphragm has teeth 7 formed around the edge thereof, which are adapted to be curved or rolled inward and under and fill 30 the groove 4, as shown at *a*, with a spring action in holding the diaphragm in place against removal.

A round cup-shaped valve 8 is mounted on the lower end of an integral stem 9 and closely 35 fits the inclosing wall of the neck B, as shown in Fig. 1. This valve is of flexible material, preferably of rubber, and gradually grows thinner from the center outward and vanishes to an elastic thin edge 10, that normally bears closely 40 against the inclosing interior neck-wall. A second diaphragm 11 is formed on the upper end of the stem 9 and is provided with a number of perforations 12, which do not register 45 with the perforations 6 in the upper dia-

phragm, and therefore prevents the insertion of an instrument or tool to fraudulently interfere with the valve. The edge of diaphragm 11 rests on an annular shoulder 13 and supports the valve controlling the discharge-passage in the suspended position shown.

The valve being spherical on the under or bottom side only leaves the thin edge 10 in contact with the surrounding neck-wall, so that when the bottle is tilted to a pouring-out position the pressure and weight of the liquid 50 contents will cause the thin edge of the valve to collapse inward and open a passage for the liquid to freely flow out through the perforated diaphragms. When the bottle is returned to a vertical position and the outward 55 flow of the liquid stopped, the thin bearing edge of the valve springs back and closes the passage against an inflowing volume should an attempt be made to fraudulently refill the bottle. The greater the pressure on the upper side of the valve the more closely the same 60 will adhere to the wall-surface.

Having thus described my invention, what I claim, and desire to secure by Letters Patent, is—

1. In a non-refillable bottle, a flexible cup-shaped valve having a spherical bottom and vanishing therefrom to a thin edge, a perforated diaphragm and a stem connecting said 70 valve and diaphragm.

2. In a non-refillable bottle, the combination with the neck part provided interiorly with an annular shoulder, of a cup-shaped valve located in the passage in the neck and having a stem formed integral therewith, and a perforated diaphragm mounted on the upper end of 75 said stem and supported from said shoulder.

In testimony whereof I have signed my name to this specification in the presence of two subscribing witnesses.

GEORGE ZISTER.
